UNITED STATES PATENT OFFICE.

DAVID L. JAQUES, OF HUDSON, MICHIGAN.

IMPROVEMENT IN ROTARY ENGINES.

Specification forming part of Letters Patent No. 43,642, dated July 26, 1864.

To all whom it may concern:

Be it known that I, D. L. JAQUES, of Hudson, in Lenawee county, in the State of Michigan, have invented certain new and useful Improvements in Rotary Steam-Engines; and I do hereby declare that the following is a full and exact description thereof, reference being had to the accompanying drawings, and to the letters of reference thereon marked.

Figure 1 is a plan view of the inner side of one of the cylinder-heads. Fig. 2 is a longitudinal vertical section through the governor, steam-chest, cylinder, &c. Fig. 3 is a view in elevation of one end of the cylinder, one of the heads being removed. Fig. 4 is a cross vertical section through the cylinder.

The engine is to be fixed vertically, as shown in the drawings, upon a suitable bed-plate.

In the several figures similar characters refer to like parts.

A indicates the cylinder, cast without heads, and provided with a semicircular crown, B, and is turned true, in the usual manner.

A' are the two cylinder-heads, each of them being provided upon the face with an annular rim, a. The heads are bolted to the cylinder in the usual manner.

I is a revolving disk secured to the main shaft H, and is of a diameter equal to the inner diameter of cylinder A, in which it revolves. This disk is provided with annular rims K and rubber packing 1, which revolve within and against the rims a a. It will be noticed that there is a rim, a, and a rim, K, on each side of the disk I.

P P P P are the four double piston-heads, two on each side of the disk I, to which they are attached, and which they make revolve. These piston-heads or steam-buckets are constructed somewhat like the buckets of a water-wheel, and, being double, may receive the pressure of the steam either from the right or left, according to the direction of revolution. They are arranged in pairs at opposite sides of the disk, and revolve in the annular space G, included between cylinder-casing A, cylinder-heads A' A', crown B, and rim a, as shown in Fig. 4. The blue lines 2 represent the packing of the piston-heads to prevent the escape of steam. It will be noticed that the inner curve of the piston-heads coincides with the outer curve of rim a, (around which it revolves,) while the outer curve is such

as to make the piston-heads act as double-ended cams for operating the cylinder valves.

S are the two cylinder-valves. They are curved, being an arc of something greater than a semicircle, and work in a semicircular groove in the crown B, and are provided with ports S'. There is a pair of these semicircular valves arranged in the crown B, so as to be parallel with, and operated by, each pair of piston heads alternately.

T is a slide-valve (operated by a screw or otherwise) in the top of the crown B, and opens or closes the cylinder-ports t t when it is desired to reverse the engine.

C is the steam-chest, which is secured upon the crown B, and is provided with a cap, D.

F is a hollow shaft passing down through cap D and steam-chest C, and is provided at its lower end with a throttle-valve, f, which admits or cuts off the steam through ports t t.

g is the spindle-valve of the governor, and plays up and down in the hollow shaft F, opening or closing the ports i i in the said hollow shaft.

o is the steam-passage to the ports i.

n is a small space around the spindle g and between the bottom of cap D and top of the main barrel of hollow shaft F. By this means a steam-pressure is obtained on the steam-chest and feed-valves, so as to prevent leaking; also to counteract the lifting force or resistance of the steam when acting upon the piston-heads.

x is the stop-cock for shutting the steam off or on.

E is a cog-wheel made fast to the hollow shaft, and conveys motion to the throttle. The standards of the governor are secured upon the top side of the wheel E, and the governor is appropriately connected to its spindle-valve g.

3 and 4 are the exhaust-pipes. 5 is the condensed-steam pipe.

In the operation of my invention, when I wish to revolve the shaft to the right, I so arrange valve T as to close the right port t and open the left port t, as in Fig. 2. Steam is then admitted through pipe o, spindle-valve g is raised, and throttle-valve opened. The steam then passes through said left port t and through the left ports S' of the semicircular valves S into the annular chamber or cylinder G, and there strikes the piston-heads P, as shown by arrows at z. The direct and the

expansive power of the steam thus let on forces that piston-head around until its ports p are opposite the exhaust 3, where the exhaust steam escapes. At this instant the most advanced points of the other pair of piston-heads are just in contact with the lower ends of the valves S. (See red lines, Fig. 2.) The impetus of the fly-wheel now forces these piston-heads P past the valves S, driving those ends of it out from the chamber G and into its recess, and causing the other ends, y , of said valves to leave the recess and descend into chamber G, as shown in dotted lines at w , in Fig. 3. In this position the steam is cut off. The same cam piston-heads continue to advance until they strike the ends y of the semicircular valves S, forcing those ends into their recess and the other ends out, thus again opening the left ports S'. In this manner the revolutions are continued. The engine is reversed by simply changing the slide valve D so as to open the right port t , instead of the left one.

It will be seen that the engine I have set forth is a double engine, having a double cyl-

inder—that is, the annular chamber G, divided into two chambers by the disk I—double piston heads P, and double valves S.

I wish it understood that I do not limit my claim to this duplication of devices, for my engine may be made single as well as double by merely dispensing with one cylinder, one set of piston-heads, and one valve.

Having thus described my invention, what I claim, and desire to secure by Letters Patent, is—

1. The piston-heads P P, constructed and operating substantially as set forth.
2. The semicircular valves S S, constructed and operating substantially as specified.
3. The combination and arrangement of the steam chest C, throttle-valve f , and governor-valve g , constructed and operating substantially in the manner and for the purposes specified.

DAVID L. JAQUES.
